UNITED STATES PATENT OFFICE.

JOHN ASHMORE AND GEORGE ASHMORE, OF PHILADELPHIA, PENNSYLVANIA.

WARP-CUTTING DEVICE FOR USE IN PILE-FABRIC LOOMS.

Application filed June 8, 1923. Serial No. 644,091.

To all whom it may concern:

Be it known that we, JOHN ASHMORE and GEORGE ASHMORE, both citizens of the United States, residing in the city and county of Philadelphia, State of Pennsylvania, have invented a new and useful Warp-Cutting Device for Use in Pile-Fabric Looms, of which the following is a specification.

Our invention relates to a class of devices
employed to sever the warps of woven fab-
rics out of which velvet, Axminster or Wil-
ton carpets, for instance, or other pile fab-
rics, are made, and which is variously
termed, in the shop as a carpet wire, and,
in untechnical language, as a cutting knife.

Confining ourselves to the expression cutting knife, it is to be explained that in pile-fabric looms a plurality of these cutting knives, identical with each other, is used, and that their curved cutting edges are drawn through the warps by various devices, the knives, from a normal plural placement in the loom, being one by one drawn through the fabric, and each, after it has done its work of cutting the warps, being returned to its original position.

As these knives have heretofore been formed, it has been necessary to constantly sharpen their cutting edges, sometimes very frequently indeed, in order to prevent the tearing of the yarn resulting in practice from the operation of these knives when their blades are dull.

It is the object of our invention to lessen
35 and almost wholly overcome the tendency of
these blades quickly to become dull, and this
object we attain by the simple expedient of
cutting an oblique slot into the outwardly
and upwardly extending curved cutting
40 edge of the blade of the cutting knife as an
entirety,—the knife being otherwise similar
in general characteristics and formation to
those which for many years have been in
use in the art of making pile fabric.

45 It should be further explained that our invention resides essentially in this construction of the cutting blade of the cutter, and that in order to effectuate the mounting and reciprocatory movement of the cutters
50 across the fabric and lengthwise of the loom, a loom the framework of which may be of any conventional or desired construction, and a means for reciprocating the cutters one by one along said framework similarly of any preferred construction operative to the end in view, are to be employed.

With the above and other objects in view our invention comprehends a novel construction of a knife which is weakened in proximity to the cutting edge, in order to provide a resilient portion and this weakening may be accomplished in many different ways.

For the purpose of illustrating our invention, we have shown in the accompanying drawings embodiments thereof which are at present preferred by us, since these embodiments will be found in practice to give satisfactory and reliable results. It is, however, to be understood that the various instrumentalities of which our invention consists can be variously arranged and organized and that our invention is not limited to the precise arrangement and organization of these instrumentalities as herein shown and described. 65 70 75

Figure 1 represents, in side elevation, a loom in conjunction with which cutters, embodying our invention, are employed.

Figure 2 represents a fragmentary perspective. 80

Figures 3 and 4 represent, respectively, perspective views of different embodiments of our invention.

Similar numerals of reference indicate corresponding parts. 85

Referring to the drawings.

1 designates a loom framework of any preferred character and 2 a cutter-carrying bed upon which are mounted our cutting knives 3, one of which detached is illustrated in Figure 3, and any desired plurality of which as mounted is illustrated in Figure 2.

As a convenient means for effecting the reciprocation or end-for-end travel of a slide 4 along the slide-way 2, we use the following connective gearing. 95

6 designates a pair of fast and loose pulleys suitably mounted upon a driving shaft 7, a pinion 8 on the free end of which shaft 7 engages with a spur wheel 9 on a driven shaft 10 suitably mounted on the framework and having at its free end a driving bevel gear 11 in engagement with a driven bevel gear 12, which being connected with a disc on which is an eccentric pin 13 serves as an eccentric,—an eccentric rod 14 making connection with the lower end 15 of a bell-crank lever 16, the upper end of which is by a link 17 connected with the slide 4. 100 105 110

Obviously, when the driving shaft 7 is caused to rotate, through the pinion 8, the

spur wheel 9, the driven shaft 10, the driving bevel gear 11, the driven bevel gear and eccentric 12, the eccentric rod 14, the bell-crank lever 16, and the link 17, the slide 4 5 will be caused to reciprocate in its slide-way 5 on the cutter-carrying bed 2.

The connection between the slide and the cutting knives is through a hook 18 pivoted to the slide 4 and adapted to engage with 10 the hook recesses 19 near the end 29 of the cutting knife 3, as particularly illustrated in Figure 3.

All of the foregoing operative devices being usual in looms of this character require no further description, but it may not 15 be improper to explain that after each cutting knife has in turn been drawn through the warps, it is moved laterally across the cutter-carrying bed 2, conveniently by the 20 properly timed operation of what we term a replacing hook 20, mounted on the free end of a transverse bar 21, which moves through a slide bearing 22 mounted on the framework and is caused so to move 25 through connection with the upper end of a rocker arm 23 pivoted at 24, the lower end of which arm travels upon a cam 25 mounted upon a cam shaft 26 housed in the framework and driven by a toothed pinion 30 27 in engagement with the spur-wheel 9, and that thereafter said cutting knife will be returned to its normal position in the plurality of knives.

28 designates the usual take-up roll for 35 the fabric which is to be operated upon.

Repeating the statement that the above described loom framework and means for reciprocating the cutters, are typical merely of devices in general use for the 40 purposes mentioned, and that other means operating to support and actuate the cutters may in their stead be employed, the cutting knife, or carpet wire as it is technically called and which is illustrated in Figure 3, 45 is the device in which our invention primarily resides and is of the following construction:—

A long shank designated by the number 3 terminates at the rear in the base or butt-end formation designated 29, the peculiar 50 outlining of which is well understood by those skilled in the art and need not, therefore, be specifically described except to say that it necessarily embodies the hook recess 55 19 into which the hook 18 on the side 4 is entered to effect the pull upon the cutter.

The advance end of the cutting knife is, however, formed into the usual outwardly and upwardly-extending curved cutting 60 blade which we have designated 30, the sides of which are oppositely curved inwardly to the cutting edge designated 31, so that viewed in transverse section the cutting blade presents, in a sense, the curvature of 65 an old-fashioned razor blade.

It is the essence of our invention to weaken the knife or cutter in proximity to its cutting edge so that the cutting portion will have a desired amount of resiliency.

In Figures 1, 2 and 3, this is accomplished 70 by forming a slit or slot 32 which is disposed substantially parallel with the bottom face of the cutter and at one end terminates in proximity to the cutting edge.

In the embodiment seen in Figure 4, the 75 cutter 33 is provided with a slot 34 which at its far end terminates in an aperture.

In all the embodiments of our invention as herein shown, we form in proximity to the cutting blades a weakened portion so 80 that the portion of the cutter which carries the cutting edge will have a desired amount of resiliency. This obviates the necessity of frequent removal of the cutters in order to 85 sharpen them, as it will be found in practice that a cutter constructed in the manner herein shown will not need to be frequently sharpened so that it is not necessary to frequently stop the loom in order to sharpen the cutters.

It will now be apparent that we have devised a new and useful warp cutting device 90 for use in pile-fabric looms which embodies the features of advantage enumerated as desirable in the statement of the invention and the above description, and while we have, in the present instance, shown and described preferred embodiments thereof which will give in practice satisfactory and reliable results, it is to be understood that these 100 embodiments are susceptible of modification in various particulars without departing from the spirit or scope of the invention or sacrificing any of its advantages.

Having thus described our invention, what 105 we claim as new and desire to secure by Letters Patent, is:—

1. A pile-wire having a blade, the cutting edge of which extends in a rearwardly direction, said blade having a slotted portion 110 the slot of which extends in a substantially parallel manner with the bottom face of the cutter and terminates at one end in proximity to said cutting edge but does not intersect said cutting edge.

2. A pile-wire having formed integral therewith a blade, the cutting edge of which extends in a rearwardly direction, said blade having a slotted portion the slot of which extends substantially parallel with the bottom face of said cutting blade and terminates at one end in proximity to the cutting edge without intersecting the same to provide a relatively flexible rear cutting portion.

JOHN ASHMORE.
GEORGE ASHMORE.
